UNITED STATES PATENT OFFICE.

JACOB ZITZERMAN, OF BROOKLYN, NEW YORK.

GOVERNOR.

Application filed June 25, 1923. Serial No. 647,577.

To all whom it may concern:

Be it known that I, JACOB ZITZERMAN, a citizen of Russia, and a resident of the city of New York, borough of Brooklyn, in the 5 county of Kings and State of New York, have invented a new and Improved Governor, of which the following is a full, clear, and exact description.

This invention relates to centrifugal speed 10 governors and has particular reference to an improvement in the construction of the governor arms.

Heretofore the arms of governors for the spring motors of talking machines have been 15 generally constructed of a leaf spring which is easily broken, thereby causing untold trouble and rendering the motor unfit for use.

It is therefore the principal object of the 20 present invention to provide an arm structure for a centrifugal speed governor of this type which reduces the possibility of breakage to a minimum, while efficiently cooperating with the other governor elements.

25 As a still further object the invention contemplates a centrifugal speed governor arm which is extremely simple in its construction, inexpensive to manufacture and which may be readily associated with or detached 30 from the component parts of the governor.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the 35 full extent indicated by the general meaning 40 of the terms in which the claims are expressed.

In the drawings—

Figure 1 is a longitudinal sectional view 45 through a governor equipped with arms constructed in accordance with the invention.

Fig. 2 is a sectional view therethrough taken approximately on the line 2—2 of Fig. 1.

50 Referring to the drawings by characters of reference, 10 designates the governor shaft which is journaled in suitable bearings 11 for rotation and has formed thereon a worm screw or other suitable means for operatively connecting the shaft to the operating de-

vice, the speed of which is to be controlled. The stationary member 13 is secured to the shaft 10 and an axially movable member 14 is mounted thereon. The members 13 and 14 are connected by the elastic governor 60 arms 15 in the usual manner and the weights 16 are carried by the arms 15 for outward movement in order to govern the speed of rotation of the shaft 10. As is usual, the member 14 upon outward movement of the 65 weights 16 is advanced toward the stationary member 13.

The governor arms 15 in the present instance each comprise an elastic tubular and normally expansible element 17 which as 70 here illustrated consists of a coiled spring, the opposite ends of which are forcibly fitted in a bushing 18, which bushings are snugly received within sockets 19 in the stationary and movable members. The elements or 75 springs 17 receive loosely therethrough a second element 20 which is non-expansible longitudinally but which has sufficient elastic properties to normally return to its initial shape. As shown the element 20 consists 80 of a small wire.

In practice the opposite ends of the wires 20 are hooked as at 21 and are engaged in notches 22 in the bushings 18. Suitable retaining screws 23 are threaded in transverse 85 bores 24 which communicate with the sockets 19 and the inner reduced ends 25 of the screws extend through openings in the bushings and engage with the ends of the coiled springs 17. The weights 16 are provided 90 with bores 26 through which the arms 15 are passed and bushings 27 surround the medial portion of the arms 15 and are engaged by retaining screws 28 which prevent accidental longitudinal or rotary movement 95 of the weights on the arms.

It will thus be seen from the foregoing construction that the springs 17 are maintained against expansion by the wires 20, while the same are allowed to flex when 100 the governor shaft is rapidly rotated to control the speed of the shaft, while the combined elastic quality of the springs 17 and wires 20 serve to normally return the parts to their original position when the rotation 105 of the shaft is reduced or brought to a stop.

I claim:

1. A centrifugal governor arm, comprising a coiled spring, and an elastic wire passing loosely through the spring and having 110

its ends secured to the ends of the spring.

2. A centrifugal governor arm, comprising a coiled spring having bushings on its ends, and an elastic wire passing loosely through the spring and having its ends secured to the bushings of the spring.

3. A centrifugal governor arm, comprising a coiled spring having bushings on its ends, the bushings having their outer ends notched, and an elastic wire passing loosely through the spring and having hooks on its ends engaging the notches of the bushings.

4. In a centrifugal governor, the combination with the governor shaft, and the movable and stationary members thereon, said members being provided with sockets, of a plurality of weight carrying governor arms having their ends in the sockets of the members, each arm comprising a coiled spring and a wire passing loosely through the

spring and having its ends secured to the ends of the spring, and means for securing the ends of the arms in the said sockets.

5. In a centrifugal governor, the combination with the governor shaft, and the stationary and movable collars thereon, said collars being provided with sockets, of a plurality of weight carrying governor arms having their ends in the sockets of the collars, each arm comprising a coiled spring having a bushing in each end, the bushings being provided with openings in their sides and notches in their ends, an elastic wire passing loosely through the spring and having hooks on its ends engaging the notches of the bushings, and a screw mounted in each collar and having its end extending through the opening of the bushing and engaging the spring.

JACOB ZITZERMAN.
